PORTABLE PICNIC CART

Ralph A. Gonzalez, 2114 Heloise Way,
Placentia, Calif. 96270

Filed July 27, 1970, Ser. No. 24,158

Term of patent 14 years

Int. Cl. D12—02

U.S. Cl. D14—3

FIG. 1 is a top plan view of a portable picnic cart showing my new design;

FIG. 2 is a front elevation view thereof;

FIG. 3 is a left side elevation view thereof, with the lid being in the open position; and

FIG. 4 is a perspective view thereof, with the side door and the lid being in the open position.

The rear and right side surfaces of the portable picnic cart, not shown, are solid and flat.

I claim:

The ornamental design for a portable picnic cart, as shown and described.
